UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
ENGLAND.

AIR-BLAST GEAR OF BREECH-LOADING ORDNANCE.

1,302,521.

Specification of Letters Patent.

Patented May 6, 1919.

Application filed April 15, 1915. Serial No. 21,621.

To all whom it may concern:

Be it known that we, Sir ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Air-Blast Gear of Breech-Loading 10 Ordnance, of which the following is a specification:

This invention relates to the air blast gear employed in breech loading ordnance for the purpose of automatically injecting into the gun breech a jet or jets of compressed air or other suitable fluid during the opening of the breech, with the object of obviating the backward rush of flame or hot gases which is liable to occur when the gun is fired in a head wind and also with the object of effectually clearing the bore of the gun of any combustible matter which may remain therein after firing.

According to this invention we employ a device which operates upon the valve that controls the supply of compressed air, and retards this valve, for a definite period of time, during its closing movement so that a prolonged blast of air can be obtained.

30 The said retarding device may be of such a character that the time occupied by the valve to return to its cut off position can be regulated at will so that the duration of the blast of air can be altered to suit various requirements. The retarding device may take the form of a dash pot comprising a vane attached to the actuating device of the control valve and disposed in a chamber which is filled with oil or other suitable liquid.

40 In order that the said invention may be clearly understood and readily carried into effect, we will describe the same more fully with reference to the accompanying drawings, in which:—

45 Figure 1 is an end elevation of part of the breech end of a gun showing our improved form of air blast gear applied thereto.

Fig. 2 is a plan of Fig. 1.

Fig. 3 is a sectional side elevation of Fig. 50 1, the section being taken approximately on the line 1, 1 of Fig. 2.

Fig. 4 is a section taken approximately on the line 2, 2 of Fig. 1, and

Fig. 5 is a section taken approximately on the line 3, 3 of Fig. 3.

55

A is the breech end of the gun, B the control valve for the compressed air which enters the breech chamber through the pipe a and the passages a' in the gun. The actuating device for the valve lever is in the example shown similar to that heretofore proposed by us, comprising a spring controlled tripping cam C' on the carrier axis pin C' which cam co-operates with the valve lever C² rigidly connected to a pivot pin c² carried by the valve casing C^{2x}. The tripping cam C' causes the valve lever C² and its pivot pin to be rocked about the axis of the latter during the opening movement of the breech carrier. This valve lever is formed with a cam C³ with which the stem of the control valve B co-operates, and is under the control of a plunger C⁴ operated by a spring c⁴ for the purpose of returning the valve lever C² when the tripping cam C' moves out of engagement with the said lever, to a position in which its cam no longer operates upon the valve stem, the valve then closing under the influence of its spring and of the air pressure. During the closing movement of the carrier the tripping cam C' is depressed by its engagement with the valve lever C² 70 without actuating the latter.

75

D represents the aforesaid vane which is attached to the pivot c² of the valve lever C² 85 so that the vane moves angularly with the said valve lever and D' represents the oil or other liquid chamber in which the vane is disposed. The said vane may as shown have two wings, each of which may be provided with a non-return ball valve d (Fig. 4). These ball valves permit the oil to flow freely from one side of the wings to the other during the opening movement of the control valve B but close when the control 90 valve commences its cut off movement so that the oil has to pass slowly between the wings and the chamber, thereby retarding the closing of the control valve. A member D³ having an adjustable by-pass d³ is in the example shown arranged above the chamber 100 D' and is retained in position by a screw threaded cap D⁴. A screw threaded plug d^{3x} passing through the member D³ serves to regulate the by-pass d³ so that the retarding 105 action of the oil can be adjusted as desired.

by obtaining a relatively free or restricted flow of the oil through the by-pass d^3 .

What we claim and desire to secure by Letters Patent of the United States is:—

- 5 1. In air blast gear for ordnance, the combination with the control valve thereof, of means for opening said valve and means for automatically retarding its closing movement.
- 10 2. In air blast gear for ordnance, the combination with the control valve thereof, of means for opening said valve during the opening of the breech and means for automatically retarding the closing movement of said valve.
- 15 3. In air blast gear for ordnance, the combination with the control valve thereof, of means for opening said valve and for releasing it during the opening of the breech and means for retarding the closing movement of said valve after release.
- 20 4. In air blast gear for ordnance, the combination with the control valve thereof, of means for opening said valve and a dashpot device for retarding the closing movement of said valve.
- 25 5. In air blast gear for ordnance, the combination with the control valve thereof, of means for opening said valve during the opening of the breech, and a dashpot device for retarding the closing movement of said valve.
- 30 6. In air blast gear for ordnance, the combination with the control valve thereof, of means for opening said valve and for releasing it during the opening of the breech and a dashpot device for retarding the closing movement of said valve after release.
- 35 7. In air blast gear for ordnance, the combination with the control valve thereof, of means for opening said valve, means for automatically retarding its closing movement and means for regulating the retardation of the valve.
- 40 8. In air blast gear for ordnance, the combination with the control valve thereof, of means for opening said valve during the opening of the breech, means for automatici-

cally retarding the closing movement of said valve, and means for regulating the retardation of the valve.

9. In air blast gear for ordnance, the combination with the control valve thereof, of means for opening said valve and releasing it during the opening of the breech, means for retarding the closing movement of said valve after release, and means for regulating the retardation of the valve.

10. In air blast gear for ordnance, the combination with the control valve thereof, of an actuating device for said valve, means for moving said device to open the valve during the opening of the breech and for then releasing the device and a dash pot device operating upon said device for retarding the closing movement of the valve.

11. In air blast gear for ordnance, the combination with the control valve thereof, of an actuating device for said valve, means for moving said device to open the valve during the opening of the breech and for then releasing the device, a rotary vane connected to said actuating device, and a fluid containing chamber in which said vane is placed to operate as a dashpot for retarding the closing movement of the valve.

12. In air blast gear for ordnance, the combination with the control valve thereof, of an actuating device for said valve, means for moving said device to open the valve during the opening of the breech and for then releasing the device, a rotary vane connected to said actuating device, a fluid containing chamber in which said vane is placed and an adjustable by-pass serving to control the passage of the fluid from one side to the other of the vane during the closing movement of the control valve.

In testimony whereof we affix our signatures in presence of two witnesses.

ARTHUR TREVOR DAWSON.
GEORGE THOMAS BUCKHAM.
